COLLAPSIBLE WIRE BOUND BOX OR CRATE

George E. Gardner, Indianapolis, Ind., assignor
to Indianapolis Wire Bound Box Company,
Indianapolis, Ind., a corporation of Indiana

Application June 29, 1936, Serial No. 87,878

8 Claims. (Cl. 217—15)

The object of my invention is to provide a polygonal crate of the external wire bound type which, when the ends of its wire bindings have been connected, may easily be repeatedly expanded and collapsed without disengagement of the connected ends of the binding wires.

A further object of my invention is to provide a blank composed of a multiplicity of serially arranged internally cleated package sides definitely connected in series by binding wires or other equivalents, wherein the cleat ends are so formed that, when the respective ends of the binding wires are connected together, the resulting structure may be collapsed without separation of the binding wires and thereafter returned to expanded relationship.

A further object of my invention is to provide a cleat the opposite ends of which are so formed that, when a multiplicity of such cleats are arranged end to end in alternating reverse relationship and connected by a binding wire, the ends of said binding wire may be connected together and the resulting structure may be caused to assume either an expanded relationship wherein each cleat lies at an angle to the immediately adjacent cleat, or may be collapsed to a position where half of the cleats lie parallel with the other half of the cleats, all without separation of the ends of the binding wire.

The accompanying drawing illustrates my invention:

Fig. 1 is an edge elevation of a crate embodying my invention with the elements thereof in assembled but collapsed relationship.

Fig. 2 is a similar elevation with the parts in expanded relationship.

Fig. 3 a perspective view of the mating ends of two cleats constructed in accordance with my invention to permit swinging movement of one cleat relative to the other from an angular relationship to a parallel superposed relationship.

Fig. 4 a perspective view of a pair of mating cleat ends of a modified form permitting swinging movement of one cleat relative to the other from an angular relationship to an aligned relationship.

Fig. 5 a plan view of a pair of mating cleat ends of the character shown in Fig. 3 with the cleats in initial aligned relationship which relationship is established during the fabrication of the blank, the connecting binding wire being omitted for the sake of clearness.

Fig. 6 an edge elevation of adjacent ends of mating cleats, of the character shown in Figs. 3

and 5, together with a portion of the connecting binding wire, and

Fig. 7 is a fragmentary view of a modified form of cleat construction for outwardly collapsing corners.

In the drawing 10, 10 indicate the cleats, which are identical except for variations in lengths to conform to the desired dimensions of the cleated structure. Each of these cleats, at one end for half or slightly more than half of its width, is beveled at 11 beginning at line 12 at the inner face of the cleat at a distance spaced from the end of the cleat approximately the thickness of the cleat and ending at the line 13 in the outer face of the cleat more distantly spaced from the end of the cleat than the tip 12. The angle of this bevel is conveniently, though not necessarily, approximately 45 degrees. The above mentioned beveling of a portion of the width of the cleat, as above described, produces a tongue 14, the inner corner of which is dubbed off at 15 to permit two cleats so formed, when reversely arranged, as indicated in Figs. 5 and 6, to be interdigitated or overlapped to an extent where the blunt tip 15t will overlie the beveled surface 11 of the adjacent cleat and the tip 12 of the beveled portion of the said adjacent cleat may lie closely adjacent and nearly in contact with the base 15b of the dubbed off portion of the first mentioned cleat, a similar relationship of said parts being also established between the second mentioned and first mentioned cleats.

The other end of each cleat 10 may be simply beveled, at 45 degrees or a little more, as indicated at 20. Preferably this beveling is at an angle slightly in excess of 45 degrees for a four-sided crate in order to make possible a slight flexibility at the corner formed by two mating cleats having this formation.

Lateral overlap of the cleats at this co-ordination may be provided, if desired, half the width of each cleat being beveled at 20a (Fig. 4) as just noted, while the other half of one cleat is left unbeveled to form the tongue 21 and the adjacent cleat is back-cut or notched to form the square shoulder 22 to mate with the inner face of the tongue 21. From a commercial aspect this arrangement is probably not very desirable because it involves a different formation for these mating ends of two cleats.

For a four-sided crate, two or more series of four cleats 10 are connected by a binding wire 30, preferably with sheet material 31 interposed between the binding wires and the outer face of the cleats 10, said cleats 10 being alternately 55

reversed with relation to each other so that there will be two diagonally disposed pairs of mating cleat ends, two of the character illustrated in Figs. 3 and 6, and two of the bevel 20 type, the 5 tips of the bevels 20 being closely adjacent and the tongues 14 being overlapped as shown in Fig. 5.

With such an arrangement a flat blank may be produced which may be then folded to the 10 relationship shown in Fig. 2 whereupon the opposite ends of each binding wire may be connected together as indicated at E in Fig. 2, each wire being drawn taut by this connecting operation to bring the inner faces of diagonally 15 opposite cleats 10 into contact with the immediately adjacent tips 12, the binding wire diagonally opposite corners A, A being drawn between the overlapped tongues 14 so as to hold the inner face of each cleat tightly against the tip 20 12 of the immediately adjacent cleat at the corners.

After this assembly has been accomplished the 25 crate may be collapsed, to the relationship illustrated in Fig. 1, where half of the cleats lie superposed upon the other half of the cleats, and the expanded relationship may be reestablished as shown in Fig. 2, by a reversal of the collapsing operation.

The formation of the cleats at the corners 30 B, B is such, as will be readily noted, that the end cleats (the vertical cleats in Fig. 2) may not be swung counterclockwise but may be swung clockwise.

In other words, in collapsing the structure the 35 cleats at the two diagonally opposite corners B may be swung from an angular relationship to an aligned relationship, whereas the cleats at the other two diagonally opposite corners A may be swung to a parallel superposed relationship. The 40 ultimate results attainable with the above described structure are the same as are obtainable with the structure which is the subject matter of my Patent 2,039,273 but specifically the cleat formation at the corners A differs.

45 The sheet material 31 is interposed between the outer faces of the cleats and the binding wire. At the corners B the sheet material may be set close to the tips of the bevels 20 while at the corners A the sheet material should be set 50 back slightly from the edges 13 so that, when the ends of the binding wires are connected, portions of the wires, at the corners B, will lie closely along the bevel surfaces 11. The cleats, for the corners B, may be formed as indicated in 55 Fig. 7, with square ends, which, when the flat blank is formed, will be spaced a cleat-thickness apart to permit establishment of the relationship shown in Fig. 7.

In the claims "wire" is used to include a band, 60 strap or other wire equivalent of suitable binding material.

I claim as my invention:

1. A container structure comprising four cleats connected in series by a binding wire associated 65 with the outer faces of said cleats, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats.

2. A container structure comprising four cleats 70 connected in series by a binding wire associated

with the outer faces of said cleats with interposed sheet material, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats. 10

3. A container structure comprising four cleats connected in series by a binding wire associated with the outer faces of said cleats, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats, each cleat at one end being formed for mating angular relation with another cleat to limit swing of one cleat relative to the other in one direction. 15

4. A container structure comprising four cleats 20 connected in series by a binding wire associated with the outer faces of said cleats with interposed sheet material, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats, each cleat at one end being formed for mating angular relation with another cleat to limit swing of one cleat relative to the other in one direction. 25

5. A container structure comprising four cleats 30 connected in series by an endless binder associated with the outer faces of the cleats, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats. 35

6. A container structure comprising four cleats 40 connected in series by an endless binder associated with the outer faces of the cleats with interposed sheet material, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of alternate pairs of cleats being overlapped beyond the inner-face tips of the beveled portions of the cleats. 45

7. A container structure comprising four cleats 50 connected in series by a binding wire associated with the outer faces of said cleats, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of alternate pairs of cleats being overlapped beyond the inner-face tips of the beveled portions of the cleats. 55

8. A container structure comprising four cleats 60 connected in series by a binding wire associated with the outer faces of said cleats, each of said cleats at one end having a part-width tongue portion subtended by a part-width portion beveled outwardly beginning at an edge in the inner face spaced from the tip of the cleat and the tongue-portion of its width dubbed off inwardly, the said tongue-portions of two adjacent cleats being overlapped beyond the inner-face tips of the beveled portions of the cleats, each cleat at one end being formed for mating angular association with the cleat adjacent that end. 65

to limit swing of one cleat relative to the other inwardly beyond a desired angular relationship.

8. A container structure comprising four cleats connected in series by a binding wire associated with the outer faces of said cleats with interposed sheet material, each of said cleats at one end having a part-width tongue portion subtended by a part-width portion beveled outwardly beginning at an edge in the inner face spaced from the tip of the cleat and the tongue-portion of its

width dubbed off inwardly, the said tongue-portions of two adjacent cleats being overlapped beyond the inner-face tips of the beveled portions of the cleats, each cleat at one end being formed for mating angular association with the cleat 5 adjacent that end to limit swing of one cleat relative to the other inwardly beyond a desired angular relationship.
